Atty.

UNITED STATES PATENT OFFICE.

GEORGE B. NORDMANN, OF NEW HAVEN, CONNECTICUT.

TROUGH.

1,297,586.

Specification of Letters Patent. Patented Mar. 18, 1919.

Application filed August 20, 1917. Serial No. 187,042.

To all whom it may concern:

Be it known that I, GEORGE B. NORDMANN, a citizen of the United States, residing at New Haven, in the county of New Haven and State of Connecticut, have invented certain new and useful Improvements in Troughs, of which the following is a specification, reference being had therein to the accompanying drawings.

10 My present invention relates to feeding or drinking troughs suitable for poultry of all sizes, but particularly useful for young chickens.

15 The object of the invention is to provide a simple, efficient and non-spillable trough which is economical both as regards its construction and use.

20 The improved device is provided with means for anointing the heads of the poultry when using the trough, such anointing being for the purpose of destroying parasites and preventing disease.

25 The invention, among other things, consists primarily in the construction and arrangement of parts as hereinafter described with reference to the several embodiments of the invention illustrated in the accompanying drawings, wherein;

30 Figure 1 is a perspective view illustrating one form of trough in which the body portion is represented as being secured to end supports;

35 Fig. 2 is a cross section of a trough designed to provide its own base or support;

Fig. 3 is a cross section showing another modified form of base.

Referring to the drawings the device consists of the supporting members 1 and the 40 intermediate body portion 2, which latter member is preferably, in this instance, of semi-circular shape in cross section, and having inwardly rolling flanges 3 and 4 provided with a stiffening crimp 5 at each edge.

45 In the construction illustrated by Fig. 1, the supporting ends 1 are secured to the body portion 2 with a joint that will permit the trough or well 6 of the body portion to hold a liquid, as well as a solid.

50 In the construction illustrated by Fig. 1, the supporting ends 1 are secured by means of ears 7 and 8 carried by the body portion and fixed by rivets 9 to the end members or supports.

55 The construction illustrated in Fig. 2 is

in all respects the same as those above described, except that the members 1 serve only to cover the ends of the trough and the body portion is provided with a flattened bottom 10, which serves as a base in lieu 60 of the supports 1. The latter form is especially useful as a water trough and can be used in several positions, without spilling the contents.

65 In Fig. 3 the base 13, having sides 14 and curved edges 15, is riveted to the bottom of the body portion 2.

An anointing device is shown, which device is equally applicable to all the embodiments or modifications. This device consists in turning the stiffening crimp 5 outwardly so that it will conveniently hold a pad or wick 16. When in operation, this wick or pad has oil or other ointment applied thereto and when young chickens for 75 example are feeding or drinking, their heads come in contact with the wick or pad and the substance thereon is applied to the heads of the chickens and also to their throats if an anointing device is provided on both 80 sides of the trough.

Light oils or other easily evaporable liquids are sometimes used as an ointment, and when employing such liquids, it is desirable to enlarge the crimp 5 to form a 85 well or reservoir 17 to receive a quantity of such liquid poured into one open end of the well, which opening is, of course, plugged after the reservoir is filled. The wick 16 is partly contained in said reservoir and held 90 in place by the serrated edge 18 of the crimp 5, and is kept constantly saturated until the supply of liquid in the reservoir is exhausted.

95 The improved trough hereinbefore described may be constructed entirely of sheet metal, or, if desired, of wood or other material, or the supporting ends may be made of wood and the trough of sheet metal. Furthermore, the improved trough may be constructed in various sizes and various lengths, according to its prospective use.

100 There are minor changes and alterations that can be made within my invention, aside from those herein suggested, and I would 105 therefore have it understood, that I do not limit myself to the exact construction herein shown and described, but claim all that falls fairly within the spirit and scope of the appended claims.

Having described my invention, what I claim as new and desire to secure by Letters Patent, is:—

1. A trough having a flanged edge and a stiffening crimp therefor, the latter forming a reservoir; and a wick protruding from said reservoir.
2. In a trough; a body portion having inwardly turning flanged edges and stiffening crimps for said edges, one of said crimps being bent outwardly to provide means for holding a wick.
3. In a trough; a body portion and a base therefor; inwardly bent flanged edges of said body portion forming a non-spillable well; and a wick carried by one of said flanged edges for applying an ointment.
4. In a trough; a continuous body portion constituting the trough proper; and a supporting base, said body portion being provided with inwardly rolling flanged edges having a well and a wick therein for applying an anointing substance by frictional contact.
5. In an article of the class described, the

combination of a body portion with a base supporting the same; a longitudinal opening in said body portion, of which opening one edge thereof is flanged and provided with a groove forming a well; and a wick for applying an ointment protruding from said groove.

6. In an article of the class described, the combination of a continuous body portion with a continuous supporting base secured on the underside thereof, a continuous longitudinal opening in said body portion and one edge of said opening being flanged and provided with a groove containing a wick for applying an ointment.

7. In an article of the class described, the combination of a body portion with a supporting base therefor and a longitudinal opening in said body portion having a flanged edge bent outwardly to form a well; and a wick protruding from said well for applying an ointment.

In testimony whereof I have hereunto affixed my signature.

GEORGE B. NORDMANN.
